HENRY H. BUTLER, OF TROY, MICHIGAN.

Letters Patent No. 74,748, dated February 25, 1868.

IMPROVEMENT IN FARM-GATES.

The Schedule referred to in these Letters Patent and making part of the same.

TO WHOM IT MAY CONCERN:

Know all men that I, HENRY H. BUTLER, of Troy, in the county of Oakland, and State of Michigan, have invented a new and useful Improvement in Farm-Gates; and I do declare that the following is a true and accurate description thereof, reference being had to the accompanying drawings, and to the letters of reference marked thereon, and being a part of this specification.

The nature of this invention consists in so hanging a farm-gate that it will never sag, but always roll easy and true. To do this I construct a gate of proper materials, with or without a centre-bar, suspended by the top rail upon two rollers journalled in the hangers, which are suspended from a horizontal bar, which runs upon a roller journalled upon and between two posts, while its outer end runs between two rollers journalled between two other posts.

In the drawing hereto attached, the gate A is hung upon two rollers journalled into the hangers B C, which are suspended from the horizontal sliding bar D. This bar D rolls upon a roller (between the hangers B C) journalled between the double posts E, which are held together at the top by a cap or any proper device. The outer end of the bar D plays between two other rollers journalled (one above and the other below the bar.) between the double posts F, which are held together at the top in the same manner as are the tops of the posts E.

By this method of construction and hanging my gate, I have it at all times so balanced that it will always work true, and without sagging.

What I claim as my invention, and desire to secure by Letters Patent, is—

1. The horizontal sliding bar D, when constructed and operating substantially as and for the purpose set forth.
2. The combination of the above with the rollers between the double posts E and F, the hangers B C with their rollers, and the gate A, when arranged, constructed, and operating substantially as and for the purposes described.

Witnesses:

J. W. HOUGHTELIN,
H. S. SPRAGUE.
